SPARK PLUG AND IGNITION LEAD WIRE
PROTECTIVE SYSTEMWilliam E. Drinkard, Birmingham, Mich., as-
signor to Chrysler Corporation, Highland Park,
Mich., a corporation of Delaware

Application December 20, 1951, Serial No. 262,604

19 Claims. (Cl. 123—143)

1

This invention relates to protective or shielding systems for protecting the spark plugs and connecting ignition wires or leads of internal combustion engines from oil, dust, moisture, and gases, and more particularly to a combination spark plug and ignition lead protective housing structure for V-type engines requiring submerged spark plugs.

Various devices have been suggested to protect the exterior portions of installed spark plugs and their immediate ignition wire connectors from moisture, dust, and oil. These have generally taken the form of plastic or flexible jackets confined to the spark plugs and the immediate wire connectors. They have not been entirely successful as protective media since the lead wires constitute conducting paths for water and/or oil to the plugs within the shield and oil-laden gases emanating from the interior structure of the spark plugs or the mounting openings therefor have often caused the shields and connecting leads to be blown off the plugs. Moreover, shields of this character have been difficult to handle especially where the spark plug was necessarily mounted in a well formed in the cylinder head of the engine.

The present invention provides a composite structure believed to better protect the plugs and lead wires of the ignition system.

An object of my invention is to provide a protective system for spark plugs and ignition lead wires that includes a spark plug shield which serves as a gasket.

Another object of my invention is to provide a protective system for spark plugs and ignition lead wires as aforesaid wherein these parts are sealed from the oil-laden vapors emanating from the valve operating mechanism of the engine.

A further object is to provide a protective system as aforesaid, wherein the spark plug is ventilated so that blowby gases from the combustion chamber leaking through the spark plug interior or through the spark plug mounting joint may get out to the atmosphere without blowing off any flashover shields provided on the spark plug and the lead wire connectors and wherein the ventilation provided in the system avoids any build-up of condensation from blowby gases.

It is also an object to provide a protective system as aforesaid, which inhibits the condensation of external water vapor within the system especially during periods of high humidity and low temperatures, and wherein the ignition lead wires emanate from the protective covering at a location permitting external water drainage away from the plug side of the leads.

2

A further object is to provide a protective system for spark plugs mounted in a well of the engine cylinder head whereby drainage water cannot get into the spark plug well.

5 These and other objects of my invention will become apparent from the following description and from the accompanying drawings wherein:

Figure 1 is an end elevation view of the rear or flywheel end of a V-8 overhead valve engine showing the ignition wire cover of my invention applied to each bank of cylinders and showing the manner of connecting the ignition wires to the distributor mounted on the engine;

Figure 2 is a top plan view of one of the lead wire covers of Figure 1;

Figure 3 is an elevational view partly in section of the structure of my invention, the section being taken on the line 3—3 of Figure 2;

Figure 4 is a sectional elevational view through the spark plug and lead wire protective structure of my invention taken at 4—4 of Figure 2; and

Figure 5 is a sectional elevation taken similarly to that in Figure 4, of a modification of my invention.

25 In the drawings in which like reference numerals designate corresponding parts of the structure of my invention, I have illustrated, as seen in Figure 1, an 8-cylinder V-type engine of current manufacture to which my invention has been applied.

The engine, as seen in Figure 1, has right and left cylinder banks 10 and 12 respectively. The cylinder banks are arranged in a V relationship, each having a cylinder head 14, the valve operating mechanism for which is enclosed beneath a cover 16 secured to the cylinder head, as seen in Figures 1, 2, and 3 by bolts 18.

Each cylinder head has a plurality of spaced cylinders 19 each provided with a combustion chamber 20 above which is a liquid cooling space 21 defined, among others, by the chamber wall 22 and a top wall 24.

40 Connecting the walls 22 and 24 on approximately one axis of the cylinders are walls 26 of circular formation which define pockets, wells, or depressions 28 for receiving and substantially submerging spark plugs 30 of conventional character. The spark plug 30 is mounted upon a seat 32 by a threaded base portion 34 which is threadedly received in a threaded bore 36 at the bottom of

45 the well which opens into the chamber 20 to permit the electrode 38 of the spark plug to be exposed to the fuel-air mixture in the chamber 20.

50 Each depression 28 preferably has its interior surface machined concentric with the axis of

the spark plug for receiving a rigid cylindrical spark plug shield or tube 40 of suitable heat-resisting and shape-retaining material, preferably steel, which is made a loose fit with the machined bore of the well 28. The lower portion of the tube 40 has an inturned lip 42 which is provided with an aperture 43 through which the threaded portion 34 of the spark plug may be inserted and whereby the lip portion 42 for the spark plug acts as a sealing gasket between the spark plug and the seat 32 and facilitates the removal and reassembly of the spark plug without the use of special tools.

The tube 40 surrounds the spark plug and extends vertically above the top wall 44 of the cylinder head cover 16, as seen at 45 in Figure 4, the said tube extending through a water and oil seal generally designated by the numeral 46.

The tube 40 is of sufficient size such that the spark plugs may easily be removed and replaced by an ordinary socket wrench, the tube 40 itself as will hereinafter be noted, serving as a tool to aid the removal and replacement of the plug. The upper end of the tube in Figure 4 is, moreover, preferably rounded or flared as at 47 and all sharp corners removed therefrom.

The seal structure 46 comprises an annular cup-like depression 48 formed in the top wall of the cylinder head cover 16 and which provides an annular cylindrical wall 49 and an annular seat 50 having an aperture 51 through which the tube 40 extends; a pressure ring or washer 52 having an aperture 53 and which is of larger diameter than the depression 48 so that it may seat upon the top wall 44 of the cylinder head cover; and a pliable annular or cylindrical sealing ring 56 of natural or synthetic plastic material, for example, rubber or "neoprene" and which is preferably a shaped preformed ring of cylindrical section having an internal dimension slightly smaller than the external dimension of the tube 40 and having at its opposite ends projecting lips 57 and 58 forming shoulders with the adjacent portion 59 of the ring.

The projection 57 is intended to be positioned in the aperture 51 of the depression 48 and the projection 58 to enter the aperture 53 of the washer 52. The portion 56 of the ring is of somewhat greater depth than the depth of the depression 48 of the cover 16 such that pressure may be brought to bear on the shouldered portions of the ring by the washer 52 when the structure is assembled as hereinafter described.

As seen in Figure 4, the insulated ignition lead wire 62 is provided with a spring contact clip 64 which snaps over the terminal end 66 of the spark plug 38 and is protected from flashover by a suitable tubular shield 70 forming no part of this invention which may be of ceramic or other suitable insulating material and which comprises an elongated tubular portion 72 embracing the lead wire 62 and extending above the spark plug a substantial height of the tube 40 and having a lower outwardly flaring lip or portion 74 which extends over the terminal connection and over a portion of the insulating wall of the spark plug.

The lead wires 62 from the individual spark plugs are turned downwardly as they emanate from the tube 40 and are arranged, as seen in Figures 2 and 3, to extend longitudinally of the cylinder head cover 16 in the direction of the rearward end of the engine where they connect with the distributor generally designated by the numeral 78.

Housing and protecting the ignition lead wires 62, is a stiff dished cover generally designated by the numeral 80 which may be of heat-resisting and shape-retaining material, for example, a metal such as aluminum and which is secured to seat upon the seal washers 52, as seen in Figure 4, and to be secured to the cylinder head cover 16 through these washers 52 by means of countersunk head screws 82 received in suitable depressions 84 of the cover 80 and threaded into suitable shoulder posts 86 projecting upwardly through the cylinder head cover 16 of which three are illustrated, which posts are suitably held to the top wall 44 of the cylinder head cover 16 as by riveting, soldering, or spot welding.

The lead cover 80 is relatively shallow in character and is of a width and length to extend over the spark plug tubes 40 and provide adequate space to neatly confine the ignition lead wires without causing damage to them. A width slightly greater than the diameter of the posts 86 plus four lead wire diameters will generally suffice for an 8-cylinder V-engine, there being four wires confined under each of the two covers provided on such an engine as is disclosed in Figure 1.

As further seen in Figures 2, 3, and 4, the cover 80 has a continuous right angled flange 91, 92, 93 which connects with the side walls 94, 95 and the end wall 96 of the lead cover 80. This flange portion may have, as seen in Figure 4, a slightly downwardly bent lip 97. The opposite flange portions 91, 92, as previously described, seat against top surface portions of the pressure washers 52 of the seals 56 and by means of the mounting screws 82, transmit compressive forces to the sealing ring 56 through the washers 52 to thus create a tight seal between the seat 50 of the depression 48 of the cylinder head cover 16 and the ring 56 and between the ring 56 and the immediately contacting wall portion of the tube 40. Unless the screws 82 effect a compression of the seal rings excessively, there will generally be an edgewise aperture 100 formed by the lip 97 of the lead cover and the top wall 44 of the cylinder head cover providing ventilation apertures between the adjacent pressure washers 52.

The end of the lead cover 80 opposite the end wall 96 is provided with a sloping wall 102 projecting downwardly and outwardly from the top wall 44 of the lead cover so as to project over the end portion of the cylinder head cover 16 and provide between this wall 102 and the rounded corner 106 of the cylinder head cover, an ignition lead outlet 108. The outer edge of the wall 102 has an additional outward flare to provide a rounded lip 110 to protect the lead wires from contact with any sharp corners.

Suitable clips or tubular confining members may be provided at the post 86 or at other points between the adjacent spark plug tubes to hold the adjacent lead wires together in a compact group such that the lead wires will stay in position after the cover 80 is removed and, moreover, to avoid sharp bends in the lead wires. These clips or tubular members may be of suitable heat-resisting insulating material and if made of metal are preferably coated and have all edges rounded. If desired, the inner surface of the cover 80 may be coated with a suitable insulating and/or rust-resisting material such as a phenolic resin coating.

Between the outlet 108 of the lead cover 80

and the distributor 78, the ignition lead wires may be clamped at one or more places against the cylinder head cover 16 by suitable straps 102a, shown in Figure 1, which are secured by bolts or screws 103 to the cylinder head 14.

It will be evident that by providing a further metallic enclosure for the exposed portions of the lead wires in Figure 1, a fully shielded enclosed ignition system to prevent radio interference from the ignition and other sources may be secured.

It will be observed that the ignition lead wire 108 is at the rearward end of the engine which end is generally lower than the front end when the engine is mounted on the vehicle chassis. By reason thereof any splash water getting under the cover 80 or on the ignition lead wires under the cover can readily run or drain off away from the spark plug chambers. Moreover, it has been previously noted that the spark plug tubes 40 project upwardly at 41 in Figure 4 above the cylinder head cover wall 44. Hence, it will be apparent that any splash water getting under the lead cover 80 and on the wall 44 of the cylinder head cover 16 cannot get into the spark plug compartment 40 and cannot get into the valve mechanism compartment by reason of the seal 46. All this is true despite the presence of the apertures 100 described aforesaid, resulting from the method of mounting the lead cover 80.

It will also be noted that any vapor emanating from the internal structure of the spark plugs 30 or through the threaded connection 34 between the spark plug well 28 and the combustion chamber 26, can find escape through the apertures 100 between the flange portion 97 of the lead cover and the top wall 44 of the cylinder head cover or through the lead wire opening 108. Moreover, fresh air can get under the lead cover throughout its periphery by reason of the aforesaid apertures to ventilate the spark plug compartments as well as the under space of the lead cover 80. The described structure, moreover, is of a character wherein it has been observed in actual use that practically no condensation forms on the under side of the lead cover 80 even under conditions providing low ambient temperatures with high humidity.

As previously indicated, the above described structure lends itself to very easy assembly of the spark plugs and of the seal structure. In actual assembly, each of the tubes 40 is provided with a seal ring 56 adjacent its upper end following which a spark plug is inserted in the tube with its threaded end 34 projecting through the aperture 43 at the bottom of the tube. A socket wrench is inserted over the octagonal portion 120 of the spark plug after which these elements are lowered into the spark plug well 28 after inserting the tube through the aperture 51 in the cylinder head cover 44 if the same is then in place. The tube 40 helps center the spark plug 34 with the threaded bore 36 and the spark plug may then be screwed in place by the wrench very rapidly. It will be observed that since the lip 42 of the tube serves as a gasket for the spark plug, there are no loose washers which may fall off the end of the spark plug in assembly or which may become lost. After the spark plug is in place, the seal ring 56 is pushed into position against the seat 50 of the depression 48 in the cylinder head cover 16, and a pressure washer 52 is placed over each ring 56. Thereafter, after the lead wires are properly arranged, the lead wire cover 80 is positioned over the wires and

tubes upon the pressure washers 52 and is secured in place by the screws 82.

It will be understood that in assembly or disassembly, the cylinder head cover 16 may be positioned after the spark plug tube 40 and spark plug are in position. In that event, the seal rings 56 must be positioned after the cover 16 is seated and must be forced over the flared end of the spark plug tube 40. Since, however, the rings 56 are very pliable, there is no difficulty in forcing them on the tube 40 over the flared lip, or to remove them from the tube in disassembly.

In Figure 5 I have illustrated a modified form of the structure of my invention wherein an O ring type seal is employed between the spark plug tube 40' in this figure, and the depression 48' in the wall 44' of the cylinder head cover 16' and wherein the lead cover 80' seats in face-to-face contact with the top wall 44' of the cylinder head cover.

As seen in Figure 5, the upper end of the tube 40 has rigidly secured thereto as by press fitting, soldering or spot welding, a right-angled sectioned pressure ring 122 having an annular cylindrical portion 123 secured on the tube and having an annular flange portion 124. The depression 48' has an annular cylindrical wall 49' and a seat 50'.

In assembling the tube and spark plug, the seal ring 56' which is preferably of pre-formed O shape section and has a somewhat smaller internal diameter than the external diameter of the tube 40' and a somewhat larger external diameter than the internal surface of the cylindrical wall 49' of the depression 48' is forced over the tube 40' and against the flange 124 of the pressure ring 122. The tube 40' is then dropped through the aperture in the depression 48' and the O ring seal permitted to rest upon the seat 50' of the depression 48'. The location of the ring 122 is such that it is necessary in mounting the spark plug to force the ring 122 downwardly against the seal to effect a compression thereof between the flange 124 of the ring 122 and the seat 50' such that the seal ring also spreads laterally to produce an effective seal between the outer surface of the tube 40' and the inner surface of the annular portion 49' of the depression to thereby create an effective vapor seal. No gasket is required between the flange portions 91, 92 of the lead cover and the top wall 44' of the cylinder head cover any unevenness between the mating surfaces serving as further means for ventilating the interior of the lead cover and the spark plug tubes.

Although it will be apparent that the illustrated embodiments of my invention are well calculated to adequately fulfill the objects and advantages of my invention described above, it will be understood that my invention is susceptible of variations, modifications and changes within the spirit and scope of the appended claims.

I claim:

1. In an internal combustion engine having a cylinder head, a spark plug relatively submerged in a well in said head, valve mechanism carried by said head and a dished cover enclosing said valve mechanism and said well; a protective structure for said spark plug and the ignition lead therefor comprising a tubular member surrounding said spark plug in said well, said tubular member having a mounting portion thereon whereby said member may be secured in said well by said plug, said member having an end open and ex-

tending through the top of said valve mechanism cover, means forming a seal between said member and said valve mechanism cover and an ignition lead cover straddling the open end of said member and mounted on said valve mechanism cover.

2. In an internal combustion engine having a cylinder head, a spark plug relatively submerged in a well in said head, valve mechanism carried by said head and a dished cover enclosing said valve mechanism and said well; a protective structure for said spark plug and the ignition lead therefor comprising a tubular member surrounding said spark plug and having one end loosely interfitting said well, said member having a mounting flange thereon whereby said member may be held therein by said spark plug, said member having its opposite end open and extending through the top of said valve mechanism cover, means forming a seal between said member and said valve mechanism cover and an ignition lead cover straddling the open end of said member and mounted on said valve mechanism cover.

3. In an internal combustion engine having a cylinder head, a spark plug relatively submerged in a well in said head, valve mechanism carried by said head and a dished cover enclosing said valve mechanism and said well; a protective structure for said spark plug and the ignition lead therefor comprising a tubular member arranged in said well and surrounding said spark plug, means on said member interengaged with said spark plug whereby the latter may mount said member in said well, said member having its other end open and extending through the top of said valve mechanism cover, means forming a seal between said member and said valve mechanism cover and an ignition lead cover straddling the open end of said member and mounted on said valve mechanism cover.

4. In an internal combustion engine having a cylinder head, a spark plug relatively submerged in a well in said head, valve mechanism carried by said head and a dished cover enclosing said valve mechanism and said well; a protective structure for said spark plug and the ignition lead therefor comprising a tubular cylindrical member loosely interfitting the wall of said well, one end of said member having an inturned lip positioned intermediate the base of said well and said spark plug and serving as a mounting means for said member by said spark plug, the other end of said member extending through the top of said valve mechanism cover, means forming a seal between said member and said valve mechanism cover and an ignition lead cover straddling said member and carried by said valve mechanism cover.

5. In an internal combustion engine having a cylinder head, a spark plug well in said head provided with a spark plug seating face, a spark plug substantially submerged in said well and mounted on said seating face, valve mechanism carried by said head, and a dished cover enclosing said valve mechanism and said well, a protective structure for said spark plug and the ignition lead therefor comprising, a cylindrical bore in said well substantially coaxial with said plug, a substantially rigid, hollow cylindrical member in loose telescoping relation with said bore, a mounting washer for said spark plug integral with said member at one end thereof and secured by said spark plug against said seating face, said washer serving as the mounting means for said member, the opposite end of said member extending through said valve mechanism cover to a position above and adjacent the top wall thereof, means providing a seal between said member and said

valve mechanism cover wall, an ignition lead cover straddling said member and means mounting said ignition lead cover on said valve mechanism cover.

5. In an internal combustion engine having a cylinder head, a spark plug on said head, valve mechanism carried by said head and a dished cover enclosing said valve mechanism; a protective structure for said spark plug and the ignition lead therefor comprising an elongated tubular member surrounding said plug and secured in said head by said spark plug, said member extending through the top of said valve mechanism cover, an annular seal mounting seat on said valve mechanism cover surrounding said member, an annular seal ring on said seat, an annular washer on said seal, and an ignition lead cover straddling said member and seated on said washer.

7. In an internal combustion engine having a cylinder head, a spark plug on said head, valve mechanism carried by said head and a dished cover enclosing said valve mechanism; a protective structure for said spark plug and the ignition lead therefor comprising an elongated tubular member surrounding said plug and secured on said head by said spark plug, said member extending through an aperture in the top of said valve mechanism cover, an annular seal mounting seat carried by said valve mechanism cover surrounding said member, a compressible seal ring on said seat, an annular washer abutting said seal, an ignition lead cover straddling said member and seated on said washer and means securing said ignition lead cover to said valve mechanism cover, said means adapted to apply sealing pressure to said ring through said ignition lead cover and washer.

8. In an internal combustion engine having a cylinder head, a spark plug relatively submerged in a well in said head, valve mechanism carried by said head and a dished cover enclosing said valve mechanism and said well; a protective structure for said spark plug and the ignition lead therefor comprising an elongated tubular member surrounding said plug in said well, said member having an annular mounting flange at one end thereof whereby it is secured to said cylinder head by said spark plug, said flange also serving as a sealing gasket for said plug, the other end of said member projecting a short distance through an aperture in said valve mechanism cover, an annular seal mounting seat carried by said valve mechanism cover juxtaposed said aperture, a compressible seal ring having a central body portion and end lip portions, one of said lip portions being received in said aperture, said body portion being positioned on said seat, a seal compressing washer abutting said ring and received over the said other lip portion of the said ring, a flanged ignition lead cover straddling said member and having its flange seated on said washer and means operating between said ignition lead cover and said valve mechanism cover for compressing said seal.

9. In an internal combustion engine having a cylinder head, a spark plug on said head, valve mechanism carried by said head and a dished cover enclosing said valve mechanism; a protective structure for said spark plug and the ignition lead therefor comprising, an elongated tubular member surrounding said plug, said member having an annular mounting flange at one end thereof whereby it is secured to said cylinder head by said spark plug, the other end of said member projecting through an aperture in the top wall of said valve mechanism cover, an

annular, depressed seal mounting seat carried by said valve mechanism cover and surrounding said member, a compressible seal ring on said seat, a seal compressing washer carried by said ring, said washer being larger than said seat and overlying said wall, an ignition lead cover straddling said member and seated on said washer and means securing said ignition lead cover to said valve mechanism cover whereby said ring is compressed and air slots are formed between said covers adjacent said washer.

10. In an internal combustion engine having a cylinder head, a spark plug relatively submerged in a well in said head, valve mechanism carried by said head and a dished cover enclosing said valve mechanism and said well; a protective structure for said spark plug and the ignition lead therefor comprising an elongated substantially rigid cylindrical member surrounding said plug, said member having an annular mounting flange at one end thereof whereby it is secured to said cylinder head by said spark plug, the other end of said member extending through the top wall of said valve mechanism cover to a predetermined point adjacent thereto, and said member having an internal transverse dimension sufficient to enable insertion therein of a socket wrench for removing said plug, means providing a seal between said member and said valve mechanism cover adjacent the top side of said top wall, an ignition lead wire within said member having a terminal clip engaged with a terminal on said spark plug, a flashover shield surrounding said lead in said member and adapted for facilitating connection and disconnection of said lead terminal clip with said plug terminal, said lead wire having a portion thereof extending over said member and arranged to be adjacent said valve mechanism cover, a shallow ignition lead cover straddling said member and ignition lead and in face-to-face relation with said top wall of said valve mechanism cover, and an aperture at one end of said ignition lead cover providing a lead outlet and ventilation port.

11. In an internal combustion engine having a pair of cylinder banks forming a V with each other, said banks being pitched downwardly longitudinally from the fan end of the engine when the latter is assembled in a vehicle, a plurality of longitudinally spaced cylinders in each bank, said cylinders having overhead valve mechanism, a plurality of spark plugs relatively submerged in wells in said heads, one being over each cylinder, and a dished cover secured to each head and covering the valve mechanism of that head; a protective structure for said spark plugs and for the ignition lead wires thereof comprising an elongated substantially rigid cylindrical member surrounding each spark plug and secured in each well by a spark plug therein, said member having an annular mounting flange at one end thereof positioned beneath said spark plug and having its opposite end extending through the top wall of said valve mechanism cover, means providing an elastic seal between each said member and said valve mechanism cover at a position within the latter cover, a detachable ignition lead wire connected to each said spark plug and extending over the tube in which it is connected, said lead wires being arranged to extend toward the low end of the cylinder bank in which they are connected, an elongated ignition lead cover secured to said dished cover and straddling all said members of one bank and the lead covers emanating from the

spark plugs therein and a lead wire aperture at the longitudinal end of said lead wire cover which is at the low end of the cylinder bank.

12. A protective structure as claimed in claim 5 11 wherein the apertured end of the ignition lead cover is located at the end of the dished portion of said valve mechanism cover and has a downwardly sloping wall extending over the lead wires and over the end of said dished portion.

13. A protective structure as claimed in claim 12 wherein said seal comprises a preformed O ring member seated on said valve mechanism cover and held under compression by a pressure ring mounted on said member.

14. In an internal combustion engine having a cylinder head, a spark plug relatively submerged in a well in said head, valve mechanism carried by said head and a dished cover enclosing said valve mechanism and said well; a protective structure for said spark plug and the ignition lead therefor comprising an elongated tubular member surrounding said plug and secured in said well by said plug, said member extending through the top wall of said valve mechanism cover, an annular seal mounting seat on said valve mechanism cover surrounding said member, an O sectioned seal ring on said seat, an annular pressure ring secured to said member and in pressure abutting relation to said seal ring, and an ignition lead cover straddling said member and seated on said valve mechanism cover.

15. In an internal combustion engine having a cylinder head, a spark plug relatively submerged in a well in said head, valve mechanism carried by said head and a dished cover enclosing said valve mechanism and said well; a protective structure for said spark plug and the ignition lead therefor comprising an elongated tubular member surrounding said plug and mounted in said well by said plug, said member extending through an aperture in the top of said valve mechanism cover, an annular seal mounting seat carried by said valve mechanism cover surrounding said member, a compressible O ring seal on said seat, an annular pressure ring abutting said seal and secured to said member, an ignition lead cover straddling said member and seated on said valve mechanism cover, and means securing said ignition lead cover to said valve mechanism cover, said member being secured in place by said spark plug and as an incidence thereto adapted to apply sealing pressure to said seal through said pressure ring whereby said seal is compressed and caused to spread laterally.

16. In an internal combustion engine having a cylinder head, a spark plug carried by said head, valve mechanism carried by said head, a dished cover enclosing said valve mechanism; a protective structure for said spark plug and the ignition lead therefor comprising a tubular member surrounding said plug, one end of said member having an inturned flange portion positioned intermediate said spark plug and head and serving as a mounting means for such member by said spark plug, the other end of said member being open and extending through the top of said valve mechanism cover, means forming a seal between said member and said valve mechanism cover, and an ignition lead cover straddling the open end of said member and carried by said valve mechanism cover.

17. In an internal combustion engine having a cylinder head, a spark plug on said head, valve mechanism carried by said head and a dished

cover enclosing said valve mechanism; a protective structure for said spark plug and the ignition lead therefor comprising an elongated tubular member surrounding said plug and carried by said head, said member extending through the top of said valve mechanism cover, an annular seal mounting seat on said valve mechanism cover surrounding said member, an annular seal ring on said seat, and engageable with said member, an annular washer on said seal, and an ignition lead cover straddling said member and seated on said washer.

18. In an internal combustion engine having a cylinder head, a plurality of spark plugs spaced apart on said head, valve mechanism carried by said head and a dished cover enclosing said valve mechanism; a protective structure for said spark plugs and the ignition leads therefor comprising an elongated tubular member surrounding each said spark plug and carried by said head, said members extending through the top of said valve mechanism cover, an annular seal mounting seat on said valve mechanism cover surrounding each said member, an annular seal ring on each said seat, an annular washer on each said seal, and an ignition lead cover straddling said members and seated on said washers there being an air slot formed between said covers intermediate said washers.

19. In an internal combustion engine having a cylinder head and a plurality of spark plugs mounted on said head in spaced relationship, each plug including a body portion and an ignition lead; a protective structure for said plugs and leads comprising tubular members surrounding the body portions of said plugs, said members having inturned flange portions at one end thereof positioned intermediate the spark plug bodies and said head and serving as mounting means for said members by said spark plugs and said members having their other ends open, and cover means carried by said head in spaced relationship to said members and straddling the open ends of said members and said leads.
